BOILER TUBE CLEANER

Filed March 26, 1926

2 Sheets-Sheet 1

Fig. 1.

This technical drawing illustrates a circular component, possibly a reel or drum, with a central slot mechanism. The central area features a slot 11 with a pair of vertical plates 12. A horizontal plate 13 is positioned above the slot. The outer edge of the component is marked with a dashed line. Numerous numbered callouts point to specific parts: 3, 36, 33, 32, 19, 34, 34, 40, 39, 43, 44, 45, 47, 46, 32, 18, 24, 31, 25, 14, 12, 27, 28, 26, 29, 50, 14, 14, 10, 15, 16, 17, 48, 49, and 14. The drawing is executed in a clear, technical style with heavy lines and cross-hatching for shading.

UNITED STATES PATENT OFFICE.

FRANK H. COLE, OF CHELSEA, MASSACHUSETTS.

BOILER-TUBE CLEANER.

Application filed March 26, 1926. Serial No. 97,550.

This invention relates to apparatus for cleaning boiler tubes, and more particularly to a device which may be permanently installed within the boiler shell, and so arranged that the operation thereof is controlled by devices located exteriorly of the boiler.

It is an object of the invention to produce a simple and comparatively cheap boiler tube cleaner having the cleaning efficiency of the well known single blower manually directed device, but arranged to simultaneously clean a plurality of tubes.

Another object of the invention is to produce a boiler tube cleaner which may be permanently attached to the inside of a boiler shell, and is capable of simultaneously operating upon a plurality of tubes, yet which is of such construction and arrangement as to occupy the minimum boiler draft space thereby offering the minimum of resistance to draft through the boiler tubes.

It is a further object of the invention to so construct a boiler tube cleaner that the tube cleaning process may be carried on during working hours without shutting down the boiler or cooling it by the opening of doors during the cleaning process.

Other objects of the invention will be fully understood from a description of the drawings and the claims hereinafter given.

Of the drawings—

Figure 1 represents a rear view of a boiler, the end cover plate or head being broken away to show the application of the invention.

Figure 2 is an enlarged detail of certain parts shown in Figure 1.

Figure 3 is a section on the line 3—3 Figure 1, certain of the parts being shown in elevation, other parts being broken away.

Like characters represent like parts throughout the several figures of the drawings.

45 Referring to the drawings—

The drawings herewith illustrate one of the many ways in which the invention might be applied, and wherein the boiler shell 10 has a smoke chamber 11 formed by the crown sheet 12 and boiler end closure or head 13, a plurality of tubes 14, and in some instances a man hole 15 having the cover 16, and clamping dogs 17.

Suitably secured to the interior of the

boiler shell is a channel like track 18 arranged to receive and guide a roller 19 from the axle 20 of which the ears 21 and 22 depend, and which form a part of an angularly hollowed casting 23, the lower end of which has a pipe 24 suitably secured thereto.

The pipe 24 is provided with a plurality of extended jets or nipples 25 which are arranged vertically thereof and coincident with the boiler tubes 14, the lower end of said pipe 24 has a short length of pipe 26 connected thereto in such manner as to form a swivel joint as indicated at 27 in Figure 3 of the drawings.

The said short pipe 26 is closed at its lower end, and is also provided with extending nipples as seen at 28 and 29, the two pipes 24 and 26 being held in swivel connection by the bolt 30.

The casting 23 has swivel joint connection 31 with a pipe 32 the upper end of which has 75 swivel joint connection 33 with the pipe 34 which in its turn is swivelled at 35 to the stationary power supply pipe 36 in which is located the valve 37.

From the foregoing it will be readily understood that there is a flexible connection from the supply pipe 36 to the casting 23 which is arranged to traverse the crown sheet of the boiler as will be explained, and a swivel connection between the pipes 24 and 26 for a purpose to be explained later.

It will be understood that the swivel joints referred to and indicated on the drawings may be of any usual or suitable construction, and if so desired a flexible metallic pipe may be employed in place of the swivelled pipes 32 and 34.

At each side of the boiler and suitably secured thereto is a sprocket wheel 38 around which and also a large sprocket 39 a chain 40 is arranged as seen in Figure 1 of the drawings, the said chain 40 being secured to the ears 41 upwardly extended from the casting 23 by a pin so that movement of the chain 40 will cause the said casting and the pipes attached thereto to traverse the boiler, this movement being an easy one to accomplish because of the fact that the weight of the said casting and its attached parts is sustained by the roller 19 which is so fitted to the track 18 as to prevent swaying of the pipe 24 in the direction of the length of the boiler.

As a steady medium for the pipe 24 after again aligning the pipe when it has against lateral swaying during its traverse across the boiler the casting 23 has laterally extended ears 41* arranged to support the 5 antifriction rollers 42 which are intended to engage the underside of the track 18.

The large sprocket 39 has a shaft 43 extending therefrom which finds a bearing in, and pierces the head 13, and at its outer end 10 has a sprocket 44 fast thereon over which a chain 45 is arranged and which also passes over the idlers 46 and 47 down to the sprocket 48 the shaft of which has the crank 49 fast thereon.

15 Preferably the sprockets are of such relative size that a quarter turn of the crank 49 will advance the casting 23 a distance equal to that between the axes of the tubes so that starting at the left, see Figure 1, the casting, 20 and consequently the pipe 24, may be advanced step by step across the crown sheet, each quarter turn of the crank causing the nipples 25 to align with a new set of tubes or column thereof until each tube has been 25 cleaned, whereupon the direction of crank movement may be reversed and the cleaning process repeated on the return movement if it is so desired.

Preferably the supply pipe 36 taps into 30 the boiler or steam drum so that live dry steam may be used, but it will be understood that air under pressure may be used in place thereof.

In the present instance the crown sheet 35 has a man hole therein the cover of which is held in place by dogs which project to such extent that they are in the path of the lower nipple or jet 29 of the short pipe 26, see Figure 3 of the drawings, the ends of the said 40 nipples 25, 28 and 29 being in close proximity to the ends of the tubes.

The tubes 14 in the side columns are fewer in number than those of the other columns, and are so arranged with relation to the 45 boiler shell that a pipe of sufficient length to accommodate the columns having the most tubes therein could not be positioned for the side columns hence the addition of the swivel joint 27 between the pipes 24 and 26.

50 As shown at the left in Figure 1 of the drawings the pipe 26 is swung out of alignment with the pipe 24, caused by the contact of the lower pipe 26 with the shell of the boiler 10 when the pipe 24 was made to 55 align with the tubes in the column at that side.

When the pipe 24 is again moved away from the side column a spring 50 is arranged to coat with the pipe 26 and cause 60 it to align itself with the pipe 24 so that the lower tubes in certain of the tube columns may be operated upon, the said spring also serving to allow the said pipe 26 to be swung to one side when the said pipe is passing the 65 clamping dogs for the man hole, and there-

It is not known that a boiler tube cleaner has ever been used wherein a boiler traversing member having an extension swiveled thereto normally out of alignment therewith but arranged to automatically align therewith at certain times, has been permanently attached inside a boiler and which was operable to traverse the tube sheet of a 75 boiler by means arranged exteriorly of the boiler, and therefore it is not the intention to limit the invention to the precise construction and arrangement shown herein as changes might be made therein without departing from its spirit and scope. 80

Having described the invention I claim.

1. The combination of a boiler having tubes therein and a boiler tube cleaner comprising a traversing member arranged in 85 said boiler and provided with a plurality of delivery outlets to register with the tubes of said boiler; means to supply steam to said traversing member; means to support said member with provision for movement, 90 and means to impart movement to said member, said traversing member having a steam delivering end section normally in alignment with the body portion thereof but movable laterally relatively thereto at times. 95

2. The combination of a boiler having tubes therein and a boiler tube cleaner comprising a traversing member arranged in 100 said boiler and provided with a plurality of delivery outlets to register with the tubes of said boiler; means to supply steam to said traversing member; supporting and guiding means for said traversing member, and means to impart movement to said traversing member, said traversing member having 105 a steam delivering end section pivotally connected with the main body portion thereof, and means to normally and yieldingly retain said end section and said main body portion in alignment. 110

3. The combination of a boiler having tubes therein and a boiler tube cleaner comprising a traversing member arranged in 115 said boiler and provided with a plurality of delivery outlets to register with the tubes of the boiler; means to supply steam to said traversing member; supporting and guiding means for said traversing member; means to impart movement to said traversing member, said member having a steam delivering 120 extension pivotally connected with one end thereof and adapted to be swung out of alignment therewith, and a spring connecting said member and its extension whereby the latter is yieldingly held in a position of 125 alignment with respect to said member with provision for lateral swinging movement of the extension when brought into engagement with the wall of the boiler.

4. The combination of a boiler having 130

tubes therein and a boiler tube cleaner comprising a laterally flexible articulated traversing member arranged in said boiler and provided with a plurality of delivery outlets adapted to register with the tubes of the boiler; means to supply steam to said traversing member; supporting and guiding means for said traversing member, and means to impart movement to said traversing member.
